UNITED STATES PATENT OFFICE.

JEREMIAH A. MOYNIHAN, OF MINNEAPOLIS, MINNESOTA.

CAR-REPLACER.

1,001,213.

Specification of Letters Patent. Patented Aug. 22, 1911.

Application filed June 10, 1911. Serial No. 632,434.

To all whom it may concern:

Be it known that I, JEREMIAH A. MOYNIHAN, a citizen of the United States, residing in Minneapolis, in the county of Hennepin and State of Minnesota, have invented 5 certain new and useful Improvements in Car-Replacers, of which the following is a specification.

My invention relates to car replacers of 10 the general kind shown in my U. S. Patent No. 987,641 of March 21, 1911, and the object of my invention is to simplify the construction whereby the replacer for one side of the track may be made of the same shape 15 as that used for the other side thereof, and whereby the parts may be rapidly adjusted to accommodate cars on either side of the track, or moving in either direction, and also whereby cars may be replaced on rails 20 of different heights whether above the ground level or on the same plane therewith.

My improvements are embodied in a combination replacer for the purposes above specified, and which is so constructed that 25 the wheels bear on their treads instead of on their flanges, as is commonly the case, the construction being such that after the wheels have thus traveled on their treads they will, when they come close to the rails, slide laterally on to the rails.

My improvements are illustrated in the accompanying drawings, in which—

Figure 1 is a plan view of a portion of a railway track with my improved car replacer in position and this figure also shows a car axle and a portion of two wheels engaging the replacers. Fig. 2 is a perspective view of one of the replacers with the approach block detached. Fig. 3 is a perspective view of the approach block. Fig. 4 is a perspective view of the coupling pin which connects the approach block with the replacer. Fig. 5 is a perspective view of the hooked bar which connects the replacer with the track. Fig. 6 is a perspective view of the key which locks the hooked bar in place. Fig. 7 is a perspective view illustrating how the approach block may be separately used to replace a car on the track when the top 50 of the rail is on a level with the platform, ground or crossing. Fig. 8 is a perspective view showing how the replacer is connected to a track when the car is moving in one direction. Fig. 9 is a similar view showing 55 the position of the parts when a car is mov-

ing in the opposite direction. Fig. 10 is an end view of the parts shown in Fig. 9. Fig. 11 is a side elevation of the parts shown in Fig. 9, the outer side plate of the replacer being broken away.

A pair of replacers is, of course, always used. They are of precisely the same construction and each consists of an outer plate A and an inner plate B, spaced apart, and rigidly connected together by cross pieces 60 C and D. The plates A and B are slightly inclined to each other, as shown in Fig. 1, converging toward their inner ends x, x' which are in use near the rails. The outer plate A is somewhat longer than the inner 65 one B. At their outer ends the plates A and B have their ends in substantially the same plane but at their inner ends or the ends next the rails the outer plate A extends a considerable distance beyond the inner end 70 of the plate B while the cross piece D extends beyond the inner end x of the plate B but terminates before reaching the outer end of the plate A. The plates A and B extend some distance above and below the upper 75 and lower sides of the cross pieces C and D so that when the treads of the wheels ride on the edges of the plates they will not come in contact with the cross pieces.

The construction of the upper and lower 80 parts of the replacer is precisely the same so that they can be reversed. In order to connect the replacer with the track, I employ a hooked bar E, the hook of which is 85 adapted to engage a rail, as illustrated in Fig. 9 while the straight part extends through one of the slots F, F' in the replacer. When the hooked bar is thus inserted it may be locked in place by a wedge 90 or key G. The slots F and F' are considerably deeper than the thickness of the hooked bar so that this bar may be tilted or adjusted to engage rails of different heights. The hooked bar is always placed through 95 the top slot. The bottom slot is used when the replacer is reversed or turned over for replacing cars coming in the opposite direction.

The cross piece C merely serves to connect the plates A and B at their upper ends 100 while the cross piece D serves this purpose and in addition serves to guide the wheels on to the tracks when they have reached the ends of the replacer. It will be observed 105 that the cross piece D extends beyond the 110

end of the plate B and is inclined downwardly and inwardly toward the track so that when the wheel on the inside of the track leaves the upper edge of the plate B 5 its flange will engage the inclined portion Z of the cross piece D and the wheel will slide laterally into engagement with the track. The wheel on the outside of the track also rides on the inner plate B, the 10 flange of the wheel being between the plate B and the adjacent rail. When this wheel reaches the end of the plate B it will pass over the track rail following the movement of the wheel on the opposite side of the 15 track. The plates A act at all times as guard plates.

H indicates an approach block. This is formed with a straight or horizontal under-surface h and an inclined upper surface h' . 20 The approach block is divided by a central space h^2 but the two parts are connected by a cross piece h^3 and another cross piece h^4 . The cross piece h^3 is arranged below the inclined surface of the block so as not to touch 25 the wheel flange and the cross piece h^4 is grooved for a similar purpose.

H' indicate arms projecting from the approach block which are formed with vertical slots i .

30 Vertical slots I are formed in the ends of the plates A and B, as indicated in Fig. 2. These are adapted to register with the slots i of the approach block which latter is connected with the plates A and B by means of 35 a coupling pin J. This connection is a loose one and the approach block thereby has a hinged connection with the plates, permitting it to move freely about the axis of the coupling pin vertically and the connection is 40 such that the inner end of the approach block may, in addition to its pivotal or hinged movement, have a vertical movement. In this way the approach block may be turned to bring its outer edge close to the 45 wheel, as illustrated in Fig. 1 and also in Fig. 11. Should the approach block extend over the edge of a tie there would be a tendency for the outer portion of the block to be tilted downward and this would tend to 50 raise the opposite end of the replacer to an objectionable extent, but by providing for a vertical movement of the inner end of the approach block relatively to the adjacent end of the replacer this objectionable feature 55 is avoided.

As before stated the replacer is reversible in order to accommodate cars to be moved in opposite directions. In Fig. 8 I have indicated how the replacer is set for cars to 60 be moved in one direction, and in Fig. 9 I have shown how the replacer is set for cars to be moved in the opposite direction. This is done by removing the approach block from the position shown in Fig. 8, turning 65 the replacer over bodily and then connect-

ing the approach block, in the manner indicated in Fig. 9, the inclined face of the approach block being always uppermost and for this reason it is necessary to disconnect it from the plates A and B when reversing. 70

It will be observed by reference to Fig. 11 that the lower edges of the plates A and B are straight, while the upper edges are inclined upwardly from their outer ends next the approach block to their inner ends 75 next the rails. This is to avoid any danger of the wheels moving sidewise away from the rails. If the wheels should be on a level with the top of the rails, as on a platform or at a crossing, the approach block may be 80 detached from the plates A and B and used in the manner indicated in Fig. 7 to guide the wheels on to the track. Fig. 7 indicates the position of the approach block when used to guide a wheel on the outside of the 85 track. The flange of the wheel in such case would be at the left of the approach block.

This combination car replacer, in which the wheels ride on their treads rather than on their flanges, can be economically constructed. The approach blocks of each pair are of precisely the same construction as are also the other parts of each replacer. This is a matter of great importance in the economy of manufacture, and not only is 95 this the case but the construction is such that the replacer may be adjusted to wheels having various relations with the track and will at all times guide the wheels properly into place on the track. 100

I claim as my invention:

1. A car replacer, comprising an inner and an outer plate, cross pieces connecting these plates, one of which is provided with an inclined upper surface extending inwardly and downwardly from the outer plate, and an approach block hinged to one end of the replacer and having a free vertical movement relatively to the replacer at its hinged end independent of or in addition to its hinged movement. 105

2. A car replacer, comprising an inner and an outer plate on the edges of which the tread of a wheel is adapted to ride, cross pieces connecting the plates one of which extends beyond the inner edge of the inner plate and is inclined downwardly therefrom, and an approach block hinged to the opposite ends of the plates. 115

3. A car replacer, comprising an inner and an outer plate, each of which has a tread-receiving edge on its upper and lower sides, cross pieces connecting the plates arranged inside the edges so as not to contact with the flange of a wheel, and an approach 125 block having an inclined upper surface and which is slotted to receive a wheel flange and has a hinged connection with said plates.

4. A reversible car replacer having an inner and an outer plate with tread-receiving 130

ing upper and lower edges, cross pieces connecting the plates one of which has an inclined surface extending beyond the end of the inner plate, and an approach block de-
5 tachably connected with the opposite ends of the plates which has a tread-receiving surface and a slot to receive a wheel flange, and which approach block when detached

from said plates may be employed to re-
place a wheel on a track.

In testimony whereof, I have hereunto
subscribed my name.

JEREMIAH A. MOYNIHAN.
